(57) **CLAIM**

We claim the ornamental design for a dental wrench, as shown and described.

DESCRIPTION

FIG. 1 is a top view of a dental wrench showing our new design.

FIG. 2 is a bottom view thereof.

FIG. 3 is a side view thereof, the opposite side view being identical.

FIG. 4 is an end view thereof, the opposite end view being identical; and,

FIG. 5 is a top perspective view thereof.

The broken lines in the drawings represent portions of the dental wrench that form no part of the claimed design.
